[57] CLAIM

The ornamental design for a container lid, substantially
as shown.

DESCRIPTION

FIG. 1 is a perspective view of a container lid showing
my new design;

FIG. 2 is a top plan view thereof;

FIG. 3 is a sectional view taken on the line 3—3 of FIG.
2;

FIG. 4 is a perspective view of another embodiment of
my new design;

FIG. 5 is a top plan view thereof; and

FIG. 6 is a sectional view taken on the line 6—6 of FIG.
5.
